UNITED STATES PATENT OFFICE.

GUSTAV PAGEL, OF BERLIN, GERMANY, ASSIGNOR TO GENERAL ELECTRIC COMPANY,
A CORPORATION OF NEW YORK.

TURBINE-DRIVEN AUXILIARIES.

1,093,145.

Specification of Letters Patent. Patented Apr. 14, 1914.

Application filed January 29, 1914. Serial No. 815,296.

To all whom it may concern:

Be it known that I, GUSTAV PAGEL, a subject of the King of Prussia, residing at Berlin, Germany, have invented certain new and useful Improvements in Turbine-Driven Auxiliaries, of which the following is a specification.

This invention relates to steam engineering, and its object is to provide means for driving the auxiliary machines used in connection with a condensing steam engine. Such auxiliaries comprise usually a circulating pump for supplying cooling water to the condenser, a pump for the water of condensation, an air pump and a boiler-feed pump. The first two pumps have to handle comparatively large quantities of water under low heads, so that they can be run at rather low speeds. The conditions are different, however, with the air pump and the boiler feed pump, which work best at a high speed. In consequence of these differences of speed it has heretofore been thought necessary to provide at least two separate motors for the auxiliary pumps, one for those which work at a relatively low number of revolutions and the other for the faster running machines. Moreover, when turbine engines have been employed to drive the pumps, it often has not been possible to connect them directly to the slowly rotating pumps, but has been necessary to interpose reducing gearing or the like.

By the present invention all the auxiliaries are driven by one steam turbine regardless of their differences in speed of revolution. This is accomplished by using a multistage turbine, and mounting the bucket wheels of different stages on separate shafts, so that the high speed machines can be driven by the shaft which has the small high pressure first stage wheel or wheels connected to it, while the low speed machines can be driven by the other shaft which carries the larger and slower low stage wheel or wheels.

The accompanying drawing shows in longitudinal section one of the embodiments of my invention.

1 indicates the casing of a steam turbine having two stages. The first or high pressure stage wheel 2 is located in a chamber 3, and is mounted on its own shaft 4, while the low pressure wheel 5 is located in a separate chamber 6 and is mounted on an

independent shaft 7. The shaft 4 is common to the air pump 8 and the boiler-feed pump 9 which are of the centrifugal type and do not need detailed description. The circulating pump 10 and the pump 11 for removing the condensed steam from the condenser are also of the centrifugal type and are mounted upon the shaft 7. High pressure steam is admitted to the first stage through a main 12 controlled by a suitable throttle valve and admitting the steam to a steam chest 13 from which it flows subject to suitable controlling means through the nozzles 14 to the buckets 15 of the first stage wheel 2. The exhaust steam from this stage flows through the nozzles 16 in the diaphragm 17 which separates the chambers 3 and 6, and acts upon the buckets of the low pressure wheel 5. The two wheels are of such relative diameters that the wheel 5 rotates more slowly than the other so as to impart to its shaft 7 and the two pumps mounted thereon a relatively low speed of revolution favorable for their best operation.

Under some circumstances it may be desirable to operate each group of pumps independently, or to drive only one group while the other is out of operation. To provide for this contingency, I have arranged an exhaust outlet 18 for the high pressure wheel opening directly into the escape pipe 19 and controlled by a stop valve 20. The low pressure end of the turbine is also provided with an inlet 21 for high pressure steam, which flows to the wheel through special nozzles 22.

The numbers of revolutions and the work performed by the two parts of the turbine may be regulated by varying in a different ratio the counter pressure of one or both of said parts. The same end may be attained by varying the ratio of supply of steam to the two bucket wheels. It is evident that in case of necessity, or from preference, exhaust or low pressure steam may be supplied to the low pressure wheel from any other source of power.

In accordance with the provisions of the patent statutes, I have described the principle of operation of my invention together with the apparatus which I now consider to represent the best embodiment thereof; but I desire to have it understood that the apparatus shown is only illustrative, and

that the invention can be carried out by other means.

What I claim as new and desire to secure by Letters Patent of the United States, is:—

- 5 1. The combination with two groups of pumps rotating at different speeds, of a multistage steam turbine having a high pressure high speed wheel and a low pressure low speed wheel, and means whereby
- 10 each wheel drives a separate group of pumps.
- 15 2. The combination with a multistage steam turbine having a high pressure high speed wheel and a low pressure low speed wheel, of independent shafts for said wheels, and a group of centrifugal pumps mounted on each shaft.
- 20 3. The combination of a multistage elastic fluid turbine having a high speed high pressure wheel and a low pressure low speed wheel, means for supplying the first wheel with high pressure steam and the second with the exhaust from the first, independent shafts for said wheels, and centrifugal pumps having different operating speeds
- 25 mounted on said shafts.

4. The combination with a multistage steam turbine having a high pressure wheel and a low pressure wheel running at different speeds, of two shafts for the two wheels, one or more pumps driven by each shaft, a 30 direct exhaust outlet for the steam from the high pressure wheel, and means for supplying steam directly to the low pressure wheel independently of the high pressure wheel.

5. The combination of a multistage elastic fluid turbine having a high speed wheel and a low speed wheel each occupying a 35 separate compartment, means for supplying steam in series to the wheels for normal operation, means for cutting out one of the 40 wheels for emergency conditions and supplying steam to only one wheel, and pumps driven by said wheels at different speeds.

In witness whereof, I have hereunto set my hand this 14th day of January 1914.

GUSTAV PAGEL.
